(57) **CLAIM**

The ornamental design for a pet accessory, as shown and described.

DESCRIPTION

FIG. 1 is a top, front, right side perspective view of a pet accessory;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is another top, front, right side perspective thereof, but shown with environmental subject matter in a state of use.

The dash-dash broken lines depict portions of the pet accessory that form no part of the claimed design.

1 Claim, 8 Drawing Sheets
